UNITED STATES PATENT OFFICE.

BRUNO HEINRICH, OF SAN FRANCISCO, CALIFORNIA.

AUTOMATIC SIGNALING, DOOR-CLOSING, AND OPERATING SYSTEM FOR ELEVATORS.

1,176,057.

Specification of Letters Patent. Patented Mar. 21, 1916.

Application filed August 5, 1913. Serial No. 783,050.

To all whom it may concern:

Be it known that I, BRUNO HEINRICH, a citizen of the United States, residing at San Francisco, in the county of San Francisco and State of California, have invented new and useful Improvements in Automatic Signaling, Door-Closing, and Operating Systems for Elevators, of which the following is a specification.

The present invention relates to an automatic signaling door-closing and operating device for automatic elevators, cars, and the like.

The object of the invention is to provide in conjunction with an electric automatic push-button-controlled elevator system, an automatic door-closing system, for the purpose of closing the door and so restoring service which otherwise would have been interrupted if a hatch door had been left open through neglect or intent, as automatic elevators should be inoperative when a hatch door is open.

A further object is to provide in conjunction with such a system a bell signal when a door is open and an intending passenger presses any one of the operating buttons on any floor or station, to bring the car to him.

A further object of the invention is to announce by a signal when the elevator is engaged, and another person intending to use it presses one of the operating buttons.

A further object of the invention is to provide a signaling system, a door-closing device, and a controlling system, each of which is operative from the same push-button.

In the accompanying drawing, Figure 1 is a diagrammatic view of my improved apparatus; Fig. 2 is a vertical section of the door latching device therein; Fig. 3 is a side view of the door-closing device therein.

Referring to the drawing, 1 indicates an electric series-wound motor, which actuates operating mechanism for an elevator car, such mechanism being not here shown.

2 are the field magnets of the motor, to which a wire 3 leads from the positive side of the main line, and from which a wire leads to two branch wires 4, terminating in contacts 5 adapted to selectively contact with contact plates 6, on direction-controlling levers or switches 7, operated by means 55 to be presently described, which contact plates 6 can also contact with contacts 8,

connected to wires 9 leading respectively to the brushes 10 of the motor, with which wires 9 are also connected wires 11, terminating in contacts 12, which selectively, 60 when either of the direction-controlling levers is operated in the manner to be presently described, contact with corresponding contact plates 13 on said contact levers, which are connected by flexible wires 65 14 to a wire 16 leading to the negative side of the main line.

Supposing that a person at any, say, the lowermost, of the floors of an elevator shaft wishes to bring to him the elevator car, 70 which is diagrammatically shown in the drawing to be located on the second floor, he closes a push button P¹ at said floor, and thereby closes a controlling circuit as follows:—from the positive side of a generator 75 17, by a wire 18 to a contact 19 of an uppermost pair of latch contacts, then by a door latch 20 to the other contact 21 of the pair, then by a wire 22 to the contact 19, door latch 20, and other contact 21, of the next 80 lower floor, and thus in like manner to the contact 21 of the lowermost floor, then by a wire 23, which is connected with a series of push buttons P¹, P², P³, by the push button P¹, by an individual wire 24 of a series to 85 the coil of a corresponding electro-magnet 25, by a common wire 26 to a spring contact 27, contact 28, wires 29, and 30, to the negative side of the generator 17. By this means 90 the electro-magnet 25 is energized corresponding to the push button which was pressed, thereby attracting the corresponding one of a series of armatures 31, and closing one of a series of operating circuits 95 as follows:—from the positive side of the main line by a wire 32 through a solenoid coil 33, then by a common wire 34, individual wire 35, individual holding coil 36, corresponding to the floor of which the push button was pressed, the purpose of which 100 coils 36 is to maintain this circuit closed after the push button is released, then by an individual wire 37, and contacts 38, which were closed by the armature 31 of the electro-magnet 25, heretofore described, then 105 by an individual wire 39 through a brush F¹ of a series of brushes F¹, F², F³, corresponding to the different floors of the shaft, which brushes contact with a selector 40, operated in a manner hereinafter described, 110 the brush F¹ being at this time in contact with one of two conducting segments 41,

which segment is also in contact with a brush D, (the other segment 41 being at this time in contact with a brush U, a circuit through which causes the car to ascend), 5 then by a wire 42 leading to one of two coils 43, of solenoids, the cores 44 of which are operatively connected to the contact levers 7 heretofore described, and thus constitute direction switches, then through a 10 wire 45, and wire 16 heretofore described leading to the negative side of the main line. By reason of the current passing around one of the solenoids 43, the contact lever 7 connected to its core is attracted, and the circuit is closed between the aforesaid plate 13 and the contact 12, and between the plate 15 6 and contacts 5 and 8.

The gearing between the motor and the car is such that, if the circuit is closed 20 through one of these contact levers, the car will begin to descend, and if through the other then the car will begin to ascend, and it will be seen that, when the push button corresponding to the first floor is operated 25 a circuit is closed such that the switch lever on the right is attracted and the car descends. Said selector is operatively connected with the car, as indicated diagrammatically, by a cable 46 around pulleys 47, 30 48, and carrying a weight 49, so that the direction switch is rotated in a clock-wise direction when the car descends, and conversely. As the car descends, the conducting segment 41 moves so that the motor controlling circuit is no longer closed between 35 the brush F¹ and the brush D and the motor stops. The intending passenger, however, cannot open the elevator door until the car has arrived at said door, for, as seen in Fig. 40 2, the door latch 20 is normally held in its operative position by a locking lever 51 having a projection 52 engaging the free end of said door latch. When, however, the car arrives at the door, a cam 53, carried upon 45 a side of the car, actuates a roller 54, and swings said lever 51 to such a position that said projection 52 no longer engages the door latch, and the door is free to be opened. Before the car stops in this position, with 50 the cam 53 engaging the roller 54, a bell circuit is closed at said floor as follows:— from the wire 18, (Fig. 1) leading from the positive side of the generator 17, by a wire 55, spring contact 56, latching lever 51, wire 57, bell coil 58, wires 59, 61, to a spring switch 62, conducting bar 63, spring switch 64 and wire 30 to the negative side of the generator 17, thus ringing the local bell 60. Said circuit was open while the car was 60 running, but is closed by contact of the parts 56 and 51, when the cam 53 engages the roller 54. Said circuit, however, is broken again after a short time, because a non-conducting disk 67, connected to the upper 65 end of a core 68 of the solenoid coil 33, falls

by gravity, as the controlling circuit is broken and the car stops, the lower end of the core 68 moving in a dash pot 71. When the disk has descended through a sufficient distance it withdraws the switch 62 from the 70 bar 63, so that the circuit is broken, and the bell 60 stops ringing. The intending passenger is thus apprised when the elevator has arrived on the floor upon which he is 75 stationed. This is of especial importance in the use of the invention for operating dumb waiters.

It is desirable that a person pressing a push button to summon a car should be apprised that the car is in use, if such is the 80 case, and that the failure of the car to come to the proper station is not due to some defect in the system. For this purpose there is provided a high resistance bell coil 73, which is interposed in a short circuit 74, 85 shunted around the contact between the spring 27 and contact point 28 hereinbefore described, when said contact is open, so that pressure on said push button rings a bell in the circuit and located in some convenient 90 point of the elevator shaft, and apprises the person summoning the elevator that the car is in use, the contact between the spring 27 and point 28 being then open, because, when the car is ascending or descending, the 95 disk 67 is in an upper position, and releases the spring 27, and thereby permits it to be out of contact with the contact point 28.

If the intending passenger has called the car to his floor landing (in this case the 100 lower floor) he opens the door by hand, and, wishing to ascend, say, to the third floor, closes the door and presses a push button p^3 of a series p^1, p^2, p^3 of push buttons in the car. He thereby closes one of a series of 105 circuits parallel respectively with the several floor push-button circuits, this parallelism being effected by an individual wire 76 leading to one side of the corresponding floor push-button P^3 and a common wire 77, 110 leading to the wire 23, which, as before explained, connects with all of said floor push buttons. It will be observed, however, that the car will not be started unless the passenger first closes the door of the shaft, for 115 unless all of said doors are closed, the controlling circuit will be broken, being converted into a signal circuit at the door latch contacts, in the manner hereinafter explained, and therefore there will be no current sufficient to operate the controlling circuit in the manner already described.

As the current passes from the positive side of the main line by the wire 32, through solenoid 33 and from there to the controlling switches, as previously described, it magnetizes the iron core 68 and draws it in an upward direction, and as the disk 67 is attached to the upper end of this core, it relieves the tension (which is upward) of the 120 125 130

springs 62 and 27, breaking the contact between 27 and 28, and cutting the high resistance bell coil of the bell 73 into the operating circuit, which becomes now inoperative for motor control, but serves for signaling as long as the motor is running. The switch spring 62 is also brought into contact with the connecting bar 63 and contact is broken between the connecting bar 63 and the spring 64, the tension of which is in a downward direction. As the bell circuit of the bells 60 is thereby broken, the bells 60 are prevented from ringing, as the cam 53 (Fig. 2) actuates the respective rollers 54 as the car passes the successive floors. When, however, the car reaches its destination, and the controlling circuit is broken at one of the brushes F^1 , F^2 , F^3 , the solenoid 33 is de-energized, allowing the magnet core 68 slowly to recede against the action of the dash pot 71; closing the contact between the spring 64 and conducting bar 63, thereby establishing the circuit as before described, and the car stops for the same reason that it stopped when arriving at the first floor, as already explained.

If, when the passenger leaves the car, he leaves the door open, the circuit between the contacts 19 and 21 is broken, but, when any of the operating buttons on any of the floors are pressed by another intending passenger, a current passes through a high resistance shunt coil 80 ringing a bell 81 (Fig. 3) and thus converting the operating circuit into a signal circuit. At the same time the current energizes magnets 82, attracting an armature 83, and closing a local circuit 84 having a generator 85, in which circuit is a magnet 86 which attracts a hook-shaped pivot- ed armature 87, which engages a hook-shaped arm 88 extending from a weighted lever 89, which lever is attached to a sleeve 92, which can slide upon a fixed horizontal bar 93 which sleeve 92 abuts against a post 94 on the elevator door 96. When the elevator door is opened, and lever 89 is pushed upward until the hook-shaped arm 88 engages the hook-shaped armature 87, in which position it remains notwithstanding the opening and closing of the elevator door, so that the ordinary use of the elevator is not interfered with. But should this door be left open then it may be again closed by the electro-magnets 82 heretofore described, by which, when energized, the weighted lever is allowed to drop, and the sleeve 92, post 94, and door 96 to move horizontally, to close the door.

It is to be understood that either the bell, or the door-closing device, or both, may be omitted, if it is thought preferable to use an inferior form of my invention.

It is to be also understood that I do not confine my invention for the use in connection with elevators only, as the above-de-

scribed operation of a power and signal or relaying devices derived from one circuit can be utilized in many ways.

I claim:—

1. In an apparatus of the character described, the combination with a car, a motor therefor, doors to which the car can move, an electric motor-energizing circuit having therein two parallel branches, arranged to conduct the current in opposite directions through the motor, a switch in each branch, a controlling circuit for selectively operating said switches and having therein two parallel branches and electro-magnetic means in the respective branches for closing the respective switches, also having therein parallel branches corresponding in number to the several doors, each having a switch therein, and also having therein a movable selector operatively connected with the car to be moved therewith, and arranged to connect either of the first-named branches in the controlling circuit with any one of the other branches therein, and means for selectively closing any one of said last-named switches, comprising an auxiliary circuit having therein for each door a pair of contacts, a door latch arranged, when in its operative position, to close said contacts, a circuit closer in said auxiliary circuit, electro-magnetic means for effecting said selective closure, a locking lever for locking said latch in its operative position, a device carried by the car arranged to engage said locking lever to withdraw the same, and a bell circuit arranged to be rendered operative by said engagement.

2. In an apparatus of the character described, the combination with a car, a motor therefor, doors to which the car can move, an electric motor-energizing circuit having therein two parallel branches, arranged to conduct the current in opposite directions through the motor, a switch in each branch, a controlling circuit for selectively operating said switches and having therein two parallel branches and electro-magnetic means in the respective branches for closing the respective switches, also having therein parallel branches corresponding in number to the several doors, each having a switch therein, and also having therein a movable selector operatively connected with the car to be moved therewith, and arranged to connect either of the first-named branches in the controlling circuit with any one of the other branches therein, and means for selectively closing any one of said last-named switches, comprising an auxiliary circuit having therein for each door a pair of contacts, a door latch arranged, when in its operative position only, to close said contacts, a circuit closer in said auxiliary circuit, electro-magnetic means for effecting said selective closure, a locking lever for locking

said latch in its operative position, and a device carried by the car arranged to engage said locking lever to withdraw the same, of a bell circuit arranged to be rendered operative by said engagement, and means, inoperative when the car is in motion, for breaking said bell circuit.

3. In an apparatus of the character described, the combination with a car, a motor therefor, doors to which the car can move, an electric motor-energizing circuit having therein two branches, arranged to conduct the current in opposite directions through the motor, a switch in each branch, a controlling circuit for selectively operating said switches and having therein two branches and electro-magnetic means in the respective branches for closing the respective switches, also having therein branches corresponding in number to the several doors, each having a switch therein and also having therein a movable selector operatively connected with the car to be moved therewith, and arranged to connect either of the first-named branches 25 in the controlling circuit with any one of the other branches therein, and means for selectively closing any one of said last-named switches comprising an auxiliary circuit having therein for each door a pair of contacts arranged to be closed only when said door is closed, a circuit-closer in said auxiliary circuit, and electro-magnetic means for effecting said selective closure, of means for breaking said auxiliary circuit 30 when the car is in motion, and a high resistance signal operating coil shunted around said break.

4. In an apparatus of the character described, the combination of a car, a motor therefor, doors to which the car can move, an electric motor-energizing circuit having therein two branches, arranged to conduct the current in opposite directions through the motor, a switch in each branch, a controlling circuit for selectively operating said switches and having therein two branches and electro-magnetic means in the respective branches for closing the respective switches, also having therein branches corresponding in number to the several doors, each having a switch therein and also having therein a movable selector operatively connected with the car to be moved there-

with, and arranged to connect either of the first-named branches in the controlling circuit with any one of the other branches therein, and means for selectively closing any one of said last-named switches comprising an auxiliary circuit having therein for each door a pair of contacts arranged to be closed only when said door is closed, a circuit-closer in said auxiliary circuit corresponding to the several doors, and magnetic means for effecting said selective closure, of means for closing said doors, and electro-magnetic means, adapted to be actuated by any one of said circuit closers, for releasing said closing means of a door which has been left open.

5. In an apparatus of the character described, the combination of a car, a motor therefor, doors to which the car can move, an electric motor-energizing circuit having therein two branches, arranged to conduct the current in opposite directions through the motor, a switch in each branch, a controlling circuit for selectively operating said switches and having therein two branches and electro-magnetic means in the respective branches for closing the respective switches, also having therein branches corresponding in number to the several doors, each having a switch therein and also having therein a movable selector operatively connected with the car to be moved therewith, and arranged to connect either of the first-named branches in the controlling circuit with any one of the other branches therein, and means for selectively closing any one of said last-named switches comprising an auxiliary circuit having therein for each door a pair of contacts arranged to be closed only when said door is closed, a circuit-closer in said auxiliary circuit, and electro-magnetic means for effecting said selective closure, of a high resistance signal coil shunted around said contacts.

In testimony whereof I have hereunto set my hand in the presence of two subscribing witnesses.
